UNITED STATES PATENT OFFICE

138,405

DESIGN FOR AN ELECTRIC SWITCH CASING

Thomas M. Cole, New York, N. Y., assignor to
Cole Electric Products Co., Inc., Long Island
City, N. Y.

Application December 18, 1943, Serial No. 112,024

Term of patent 14 years

(Cl. D26—13)

To all whom it may concern:

Be it known that I, Thomas M. Cole, a citizen of the United States, residing at the city of New York, county of New York, and State of New York, have invented a new, original, and ornamental Design for an Electric Switch Casing, of which the following is a specification, reference being had to the accompanying drawings, forming a part thereof.

Fig. 1 is a perspective view of an electric switch casing, showing my new design;

Fig. 2 is a top plan view thereof;

Fig. 3 is a view in elevation of one end of said casing, the opposite end having the same appearance;

Fig. 4 is a view in elevation of one side of said casing, the opposite side having the same appearance.

I claim:

The ornamental design for an electric switch casing, as shown and described.

THOMAS M. COLE.
